(57) **CLAIM**

The ornamental design for a holder for cup-shaped capsules, as shown and described.

DESCRIPTION

FIG. 1 is a perspective view of holder for cup-shaped capsules showing my new design;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof;

FIG. 8 is a perspective view showing, in broken lines, cup-shaped capsules on the holder; and,

FIG. 9 is an alternative perspective view showing, in broken lines, cup-shaped capsules and additional holder elements. The broken lines in the drawing are included for the purpose of illustrating environment that forms no part of the claimed design.
